Patented Apr. 1, 1924.

UNITED STATES PATENT OFFICE.

EDWARD B. HESS, OF MANHATTAN BEACH, NEW YORK, N. Y., ASSIGNOR TO ROYAL
TYPEWRITER COMPANY, INC., OF NEW YORK, N. Y., A CORPORATION OF NEW YORK.

TYPEWRITING MACHINE.

Application filed October 12, 1921. Serial No. 507,177.

To all whom it may concern:

Be it known that I, EDWARD B. HESS, a citizen of the United States, residing at Manhattan Beach, in the county of Kings, New York, and State of New York, have invented certain new and useful Improvements in Typewriting Machines, of which the following is a specification.

This invention relates particularly to typewriting machines of the front strike, visible type, in which the type-bar segment is arranged obliquely or at an angle to the horizontal plane of the key levers and the platen is mounted in a carriage which is raised and lowered obliquely for ease printing. Such constructions are well adapted for use in small portable machines where the platen is held well down toward the base of the machine and the type-bars are held in fan-shape below the line of vision. In such machines as heretofore constructed, when the keys are operated the type-bars are moved quickly to the printing point on the platen which is behind a vertical plane, passing through the pivots of the type-bars and above a horizontal plane passing through the axis of the platen. Ordinarily the type-bars are moved from their positions of rest with accelerated speed to the platen and strike it sharply and in such manner as to produce considerable noise. The object of the present invention is to as far as possible reduce this noise and I accomplish this by a novel construction of type action which is similar, broadly considered, to that shown in my U. S. Patent No. 1,390,708, of September 13, 1921, but it involves certain novel features by means of which the broad features of said patent are best adapted to a machine in which the type-bar segment and the platen carriage are arranged obliquely.

In carrying out my invention and applying it to a machine in which the segment and the carriage are arranged obliquely, I pivotally connect the type-bars to the oblique segment and support their outer or front ends in such manner that they normally, or when at rest, are inclined slightly from their rear ends upwardly and forwardly. The key levers are horizontally arranged and they are connected to the type-bars by links and levers which are such that when a key is depressed to its full extent the associated type-bar is moved to a position considerably in advance of the platen, at

which time the connections between the type-bar and the key lever assume a dead-center or toggle-locking position and the type-bar is moved no further by the key but, owing to the momentum of the type-bar acquired during its excursion toward the platen, it is carried by its momentum to the printing-point beyond the platen. By reason of this operation the noise produced by the impact of the type-bar on the platen is materially reduced. These connections between the key levers and the type-bars comprise two-armed or bell-crank levers which are mounted over the key levers and between their opposite ends. One arm of each lever is link-connected to an associated key lever and the other arm is link-connected to the heel of an associated type-bar. When a key is depressed to its full extent, the associated two-armed lever is moved to a position in which the pivot points between its link, the key lever and the axis about which it turns reaches a dead-center or toggle-locking position so that the key lever cannot further descend and the type-bar reaches a position considerably in advance of the platen above the pivot of the type-bar but, owing to the momentum of the type-bar it is carried to the platen in such manner as to reduce noise as before explained. During this operation also, when a key is fully depressed the pivot points between the two-armed lever, the link, the type-bar and the pivot of the type-bar assume a dead-center position, but this position is changed when the type-bar moves by its momentum to the platen. By reason of these connections which assume dead-center or toggle-locking positions a noise-reducing type action for an oblique machine is obtained, which experience has demonstrated operates most efficiently.

The escapement mechanism for the carriage, which is of the same general construction as that used in the Royal standard machine, is so modified as to operate more efficiently in connection with the noise-reducing type action of the kind hereinbefore specified. According to my present invention the universal bar is mounted below the pivots of the type-bars and is connected with the type-bars or the pull links thereof by other links which are of such construction that they operate to move the universal bar only during the latter part of the movement of the type-bars preferably during what is

termed the "momentum period" thereof. The universal bar is link-connected to a lever associated with the escapement rocker in such manner that the rocker is operated 5 after the lever has been moved to some extent, so that the escapement mechanism is actuated during the momentum period of the type-bars or just as the type strike the platen and thus double impressions or blur- 10 ring of the print is prevented.

In the accompanying drawings,

Figure 1 is a view, partly in longitudinal section and partly in side elevation, of a portion of a typewriting machine embody- 15 ing my improvements;

Figure 2 is a detail view on an enlarged scale of portions of the mechanism showing particularly the manner of connecting the type-bars with the universal bar and the de- 20 vices employed for connecting the universal bar with the escapement. Fig. 2 shows the position of the parts at the time that the type-bar strikes the platen.

A portion of a typewriter carriage is in- 25 dicated at A and B indicates a platen. A type-bar segment is indicated at C, a key lever at D and a type-bar at E. E' indicates a type-bar guide. It will be observed that the segment C is arranged obliquely or at 30 an angle to the horizontal plane of the type-bars. Each key lever is pivoted at its rear end e in a frame F. It is held normally in a horizontal position by a spring f and its upward movement is limited by a cushioned 35 stop d. Each type-bar is pivoted at c to the segment C and its type-carrying end normally rests on a cushioned stop G.

It will be observed that the type-bar seg- 40 ment is inclined rearwardly and upwardly from its lower end and that the typewriter carriage is correspondingly obliquely in- 45 clined. The shift rail H may be connected with any suitable mechanism for raising and lowering the carriage obliquely. Appropri- 50 ate mechanism for this purpose is shown in my application for patent filed May 27, 1921, No. 473,164. The escapement mechanism J is also obliquely inclined and is raised and lowered with the carriage in the manner shown in said application of May 27, 1921.

It will be observed that the front face of the platen is located in a plane considerably in rear of a vertical plane passing through 55 the pivots of the type-bars and it is therefore necessary to so construct the type action as to carry the type-bars beyond the vertical plane of the pivots. Heretofore this has been done by a direct continuous action of the key levers, but by my present improve- 60 ments a full depression of a key lever moves the associated type bar only to a position considerably in advance of the platen, the further movement of the type-bar to the platen being caused by the momentum there- 65 of. As shown in Fig. 1 by dotted lines at X,

the type-bar is moved by a full depression of an associated key to a position in which the face of the type is in substantially the same vertical plane as the pivot of the type- 70 bar. The dotted lines Y indicate the impact position to which the bar is carried by its momentum.

In order to provide a type action for per- 75 forming the operations above explained, I employ a series of two-armed levers K, in-

dividually pivoted to a rod L, mounted in the front part of the machine frame above the key levers. The lower forwardly extending arm of each lever is connected by a link 80 M with a key lever. Each link M has its

ends pivotally connected with a lever K and a key lever D, and each link extends down- 85 wardly and rearwardly from a lever K to a key lever beneath it. The upper and shorter arm of each lever K is connected by a link N with the heel of a type-bar, the connection between the link and the two-armed lever and the type-bar being pivotal so as to give 90 freedom of movement. It will be observed that the point of connection between the rear end of the link N and the associated type- 95 bar is below and slightly in advance of the pivot of the type-bar and that normally the link is moved from its rear end upwards and forwards. When a key is depressed to 100 its full extent the parts move from the position shown by full lines in Fig. 1 to those shown by dotted lines, the type-bar being in the position indicated at X. At this time the point m of connection between the link 105 M and the lever K is moved downwardly and rearwardly until it comes into a direct line with the axis of the rod L and the point of connection m' between the link and the key lever. This is a dead-center or toggle- 110 locking position. There is no further depression of the key lever and the type-bar is not moved further toward the platen by the key but the type-bar is carried from this dead-center or toggle-locking position to the 115 platen, as indicated at Y, by its momentum. During this momentum period the key lever moves upward to a slight extent and the toggle lock is broken, the point m moving forward and not rearwards, as before. Dur- 120 ing this operation also the upper short arm of the lever K moves forward and pulls the link N forwards in such a manner as to raise the type-bar to the position indicated at X and when the type-bar reaches this position 125 the point n where the link connects with the type-bar moves to the position shown at z, which is in a direct line with the pivot of the type-bar and the point n', where the link N connects with the lever K. This is also a dead-center or toggle-locking position, but is broken by the momentum of the type- 130 bar as it moves from X to Y, the link then moving to the position indicated at z'. In this way I have provided means for reducing

noise in a machine where the platen is arranged in a low horizontal plane and is moved obliquely with its carriage when shifted.

5 In connection with improvements hereinbefore explained, I provide novel mechanism for operating the escapement. A universal bar is indicated at O. It comprises arms o, carried by a rod O' and connected 10 by a rod P, which is operatively related with a series of links Q, extending from the pull links N of the type-bars. There is one such link Q for each such type-bar and each link is pivotally connected with 15 a clip or pendant q on the link N near its rear end. Each link Q extends downwardly and rearwardly from the associated link N and is provided with a loop q', through which the rod P extends, the arrangement 20 being such that when a type-bar is raised and moved forwards the universal bar is not at first moved but as soon as the type-bar reaches the momentum period indicated at X the link Q engages the rod and the 25 universal bar is operated while the type-bar is approaching the platen. Each type-bar is returned to normal position and held on its rest against vibration by a spring R.

The escapement mechanism is in general 30 similar to that used in the standard Royal machine and it is also similar to that shown in my application of May 27, 1921, above referred to, but it will be observed that the rocker-plate j, which carries the feed 35 pawls, is pulled forward by a spring S and a lever T is provided which is pivotally mounted at t on the escapement frame and is connected at its lower end by a link U with the upper rear end of the arm o of the 40 universal bar. The lower end of the lever T is drawn rearwards by a spring V, connected at v to a support W and at v' to the lever.

When the lever T is drawn forward it 45 first moves without operating the escapement, but then strikes the adjustment screw T' on the rocker and the pawls are released. When the lever is released its rearward movement is limited by a stop t', which 50 strikes the frame at t'.

The link U and the spring V are so arranged and connected that the relation of the parts is preserved when the carriage is shifted and they operate in the same way 55 and at the same time during both upper and lower case printing. The links Q are obliquely arranged, i. e., they extend downwardly and rearwardly from the rear ends of the pull links N, being preferably arranged at an angle of about 45°. When 60 the type-bars are raised to the position shown in Fig. 2, i. e., to the position where they strike the platen, the obliquity of the links is changed and they are more nearly 65 vertical, the rod P being moved from a

position in rear of the vertical plane of the type-bar pivots forwardly but to a position still lying in the rear of said plane so that when the impression has been made a direct pull is imparted by the universal bar on 70 the type-bars which causes them to be returned easily to normal position. When the type-bars are being pulled back the links N are turned about the points n' by the links Q, which are connected to the remote 75 rear ends of the links N so that a long leverage is provided which facilitates the operation. I have found that by employing the constructions just described the springs f for returning the key levers to normal 80 position may, if desired, be omitted, or be made much weaker or smaller than would otherwise be required. As before stated, the connections between the lever T and universal bar are such that the mechanism operates in the same way when the carriage is shifted for either upper or lower case printing. In Fig. 1 dotted lines indicate the positions of the springs V and the links U 85 when shifted for upper case printing. While 90 the links Q are preferably connected to the pull links N in the manner shown, good results may be obtained by connecting said links with the type-bars in other ways.

I claim:

1. In a typewriting machine, the combination with the platen of a pivotally mounted type bar, a key lever, a two-armed lever interposed between the type bar and the key lever, a link connecting the two-armed 100 lever with the key lever, and another link connecting the two-armed lever with the type bar at the point below and in advance of the type bar pivot, a full depression of the key lever moving the 105 connections to a position in which the link connected to the type bar lies in a straight line with the type bar pivot and the type bar occupies a vertical position from which it moves to the platen by momentum alone. 110

2. In a typewriting machine, the combination with the platen of a pivotally mounted type bar, a key lever, a two-armed lever interposed between the type bar and the key lever, a link connecting the two-armed lever 115 with the key lever, and another link connecting the two-armed lever with the type bar at a point below and in advance of the type bar pivot, a full depression of the key lever moving the connections to a position 120 in which the link connected to the type bar lies in a straight line with the type bar pivot and the link connected to the key lever lies in a straight line with the pivot of the two-armed lever, while the type bar occupies a vertical position from which it moves to the platen by momentum alone. 125

3. In a typewriting machine the combination with the platen of a pivotally mounted type bar, a key lever, a two-armed lever in- 130

interposed between the type-bar and the key lever, a link connecting the two-armed lever with the key lever which is inclined rearwardly and downwardly from its upper end and a link connecting the other arm of the two-armed lever with the heel of the type bar, the connections being movable to such an extent that when the key is fully depressed the link connections assume a dead-center or toggle-locking position when the type bar reaches a vertical position considerably in advance of the platen, the further movement of the type bar to the platen being caused by its momentum which carries it rearwardly to the printing point behind the vertical plane of the type bar pivots.

4. In a typewriting machine the combination with the platen of a pivotally mounted type bar, a key lever, a two-armed lever interposed between the type bar and the key lever, a link connecting the two-armed lever with the key lever which is inclined rearwardly and downwardly from its upper end, and a link connecting the other arm of the two-armed lever with the heel of the type bar below its pivot, the connections being movable to such an extent that when the key is fully depressed the link connections between the two-armed lever and the type bar and between the two-armed lever and the key lever assume a dead-center or toggle-locking position when the type bar reaches position considerably in advance of the platen, the further movement of the type bar to the platen being caused by its momentum which carries it rearwardly to the printing point behind the vertical plane of the type bar pivots.

5. In a typewriting machine the combination with the key levers, the type bars and connections therebetween, of escapement

mechanism, a universal bar mounted below the type bar pivots, links inclined forwardly and upwardly from their lower ends and operatively connected with the type bars, a lever operatively connected with the escapement mechanism, and a link connection between said lever and the universal bar which is inclined forwardly and upwardly from its rear end.

6. In a typewriting machine the combination with the key levers, the type bars and connections therebetween, of a universal bar mounted below the type bar pivots, links extending forwardly and upwardly from the universal bar to the type bars and equipped with means for providing lost motion, a lever operatively connected with the escapement mechanism, and a link connected with said lever inclined forwardly and upwardly therefrom and connected at its front end with the universal bar.

7. In a typewriting machine the combination of an obliquely-arranged segment, an obliquely-arranged platen carriage, type bars pivotally connected with the segment, key levers operatively connected with the type bars, escapement mechanism, a universal bar located below the pivots of the type bars, links connected with the type bars extending downwardly and rearwardly therefrom and joined with the universal bar by lost motion connections, a lever associated with the escapement, a link connecting said lever with the universal bar which when the universal bar is operated moves without operating the escapement mechanism but thereafter actuates said mechanism, and means for returning said lever and parts connected therewith to normal position.

In testimony whereof, I have hereunto subscribed my name:

EDWARD B. HESS.
